UNITED STATES PATENT OFFICE.

LEONARDO GUARDINO, OF BROOKLYN, NEW YORK.

DESIGN FOR AN AUTOMOBILE SIGNAL-LIGHT CASING.

Application filed March 25, 1922. Serial No. 1,381. Term of patent 14 years.

To all whom it may concern:

Be it known that I, LEONARDO GUARDINO, a citizen of the United States, and a resident of the city of New York, borough of Brooklyn, in the county of Kings and State of New York, have invented a new, original, and ornamental Design for an Automobile Signal-Light Casing, of which the following is a specification, reference being had to

the accompanying drawing, forming part thereof.

Figure 1 is a rear elevation of the device; and

Figure 2 is a side elevation thereof.

I claim:

The ornamental design for an automobile signal light casing, as shown.

LEONARDO GUARDINO.
